(57) **CLAIM**

The ornamental design for a gateway for home network, as shown and described.

DESCRIPTION

FIG. 1 is the front perspective view of a gateway for home network showing our new design;

FIG. 2 is the front view thereof;

FIG. 3 is the rear view thereof;

FIG. 4 is the left-side view thereof;

FIG. 5 is the right-side view thereof;

FIG. 6 is the top-side plan view thereof;

FIG. 7 is the bottom-side plan view thereof; and,

FIG. 8 is another front perspective view thereof, as shown in an alternate configuration.

The broken lines are for environmental purposes only and form no part of the claimed design.
